DESIGN FOR A FISHING ROD HANDLE

John S. Burdick, Buffalo, N. Y., assignor to The American Fork & Hoe Company, Cleveland, Ohio, a corporation of Ohio

Application June 29, 1934, Serial No. 52,386

Term of patent 14 years

To all whom it may concern:

Be it known that I, John S. Burdick, a citizen of the United States, residing at Buffalo, in the county of Erie and State of New York, have invented a new, original, and ornamental Design for Fishing Rod Handles, of which the following is a specification, reference being had to the accompanying drawing, forming a part thereof, in which Figures 1 and 2 are perspective views showing my new design.

I claim:

The ornamental design for a fishing rod handle substantially as shown.

In testimony whereof, I hereunto affix my signature this 18th day of June, 1934.

JOHN S. BURDICK.
